ESCUTCHEON PLATE

Hunt Lewis, Arcadia, Calif., assignor to Schlage Lock
Company, a corporation

Application July 30, 1958, Serial No. 51,990

Term of patent 14 years

(Cl. D50—6)

Fig. 1 is a perspective of an escutcheon plate, showing my new design;

Fig. 2 is a front elevation of the escutcheon plate; and

Fig. 3 is a vertical cross section through the escutcheon plate as taken along line 3—3 of Fig. 2.

I claim:

The ornamental design for an escutcheon plate, as shown.
